WINE PUMP

Gregory C. Lutz, Chicago, Ill.

Application April 16, 1952, Serial No. 19,350

Term of patent 14 years

(Cl. B2—3)

To all whom it may concern:

Be it known that I, Gregory C. Lutz, a citizen of the United States, residing at Chicago, in the county of Cook and State of Illinois, have invented a new, original, and ornamental Design for a Wine Pump, of which the following is a specification, reference being had to the accompanying drawing, forming a part thereof, in which:

Fig. 1 is a front elevational view of a wine pump embodying my new design;

Figs. 2 and 3 are, respectively, fragmentary left and right hand side elevational views of the wine pump shown in Fig. 1; and

Figs. 4 and 5 are, respectively, top and bottom views thereof.

I claim:

The ornamental design for a wine pump, substantially as shown.

GREGORY C. LUTZ.
